UNITED STATES PATENT OFFICE.

EDWARD M. JOHNSON, OF PAWNEE CITY, NEBRASKA.

HAY TRACK HANGER.

Application filed August 3, 1927. Serial No. 210,372.

This invention relates to a hay track hanger, and has for its object to provide, in a manner as hereinafter set forth, a hanger of such class capable of being quickly connected to and supported from the roof rafters of a barn without employing holdfast devices, such as nails, screws and bolts to secure the hanger in position and which when employed generally result in the splitting of the rafters.

Further objects of the invention are to provide a hay track hanger, in a manner as hereinafter set forth, which is simple in its construction and arrangement, strong, durable, compact, thoroughly efficient in its use, conveniently installed with respect to the roof rafters and the track, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claim hereunto appended.

In the drawings wherein like reference characters denote corresponding parts throughout the several views:

Figure 1 is a cross sectional view of the roof of a barn, showing the adaptation with the rafters thereof, of a hay track hanger in accordance with this invention suspending a track rail.

Figure 2 is a sectional side elevation, partly broken away, of a hanger in accordance with this invention.

Figure 3 is a vertical sectional view of the coupling element for supporting and suspending the hanger members.

Figure 4 is a perspective view of the coupling element.

Figure 5 is a perspective view illustrating the oppositely disposed hanger members.

Referring to the drawings in detail 1 denotes a roof including oppositely disposed rafters 2, 3 which are spaced from the roof 1 by supporting planks 4 whereby spaces 5 are provided between the rafters and the roof body. The supporting members or planks 4 are arranged in spaced relation.

A hay track hanger in accordance with this invention comprises a coupling member consisting of a horizontally disposed bar,

standing on edge, of appropriate length and width and which is indicated at 6 and provided centrally of its upper longitudinal edge with a notch 7 which provides a seat. 60 Connected to each end of the bar 6 is an upstanding hook member 8 capable of being angularly adjusted relative to the bar 6 and adapted to seat on the top edge of the rafter, as well as overlap the same, as shown in 65 Figure 1, whereby the coupling element is detachably connected to and supported from a pair of rafters.

Extending through each end of the bar 6 and a lower end of the hook member 8 is a 70 bolt 9, carrying a securing nut 10 and a resilient washer 11. The heads of the bolts 9 are countersunk in the bar 6 and the shanks of the bolts project from the hook members 8. The washers 11 are interposed between the hook members and the nuts 10. After the hook members have been adjusted to the desired position, with respect to the bar 6, the nuts 10 are screwed home, and in connection with the washers 11 fixedly maintain the hook members 8 in adjusted position. 75 Suspended from the bar 6, is a pair of oppositely disposed hanger members and each of which consists of a shank 12 provided with a plurality of spaced openings 13. 80

The upper ends of the shanks 12 terminate in a circular hook 14 and the lower ends of the shanks 12 each terminate in a hollow semi-circular extension 15 which is disposed at right angles to the plane of the shank 12. 90 When the hanger members are in active position, they abut against each other and the hooks 14 thereof are oppositely disposed, but the extensions 15 oppose each other. The extensions 15 when the hanger members are 95

in abutting engagement are also oppositely disposed. The extensions 15 form grips for the head 16 for the track 17. The hanger members are detachably secured together, by holdfast devices 18 which extend through the openings 13 of the shanks 12 and said holdfast devices 18 provide means to maintain the grips formed by the extensions 15 in clamping engagement with respect to the head 16 of the track 17. 100

When the hanger members are in position to suspend the track 17 the hooks 14 are so disposed to form an annulus and which is seated in the notch 7 and under such conditions the hangers are prevented from removal from the bar 6 until the holdfast devices 18 are removed to permit of the separation of the hanger members, 105 110

and after the holdfast devices are moved the hanger members can be lifted from the bar 6. The hooks 14 of the hanger members provide means for securing said members to the bar 6. The construction and arrangement of the coupling element is such that it can be positioned, with respect to the rafters, without the employment of holdfast devices to secure said element in position. The bar 10 6 of the coupling element provides a suspension means for the hanger members and the semi-circular extensions 15 of the hanger members act as grips or clamps for securing the tracks 17 to said members.

15 It is thought the many advantages of a hay track hanger, in accordance with this invention, as it is capable of being quickly connected to and supported from the roof rafters without the employment of holdfast devices, can be readily understood, and although the preferred embodiment of the

invention is as illustrated and described, yet it is to be understood that changes in the details of construction can be had which fall within the scope of the invention as claimed.

What I claim is:

A hay track hanger comprising a coupling element including a pair of angularly adjustable hook members for overlapping a pair of rafters, and a pair of oppositely disposed detachably connected hanger members including means for securing them to said element for suspension therefrom and further including a pair of oppositely disposed grips for the track, and said coupling element further including means for maintaining said hook members in adjusted position.

20 In testimony whereof, I affix my signature hereto.

EDWARD M. JOHNSON.
